METHOD OF PAINTING AND PRESERVING ART GLASS

Filed Dec. 9, 1927

UNITED STATES PATENT OFFICE.

JOHN MACQUARRIE, OF SAN FRANCISCO, CALIFORNIA, ASSIGNOR TO CHAS. WALTER,
OF SAN FRANCISCO, CALIFORNIA.

METHOD OF PAINTING AND PRESERVING ART GLASS.

Application filed December 9, 1927. Serial No. 233,947.

This invention relates to a novel method of simulating art glass work and has for its principal object the arrangement or association of a painted glass panel with a protective glass covering therefor, whereby a pleasing decorative effect is realized that is economical to manufacture, and highly ornamental in appearance.

A further object of the invention is to provide a unique method of the character described, that is simple in arrangement and that will produce an article that is durable and that further embodies in its construction the feature whereby the danger of the decorative surfaces being discolored will be eliminated.

Other objects and advantages will be apparent during the course of the following description.

20 In the accompanying drawings forming a part of this specification, and in which like numerals are employed to designate like parts throughout the same,

Figure 1 is a perspective view of the assembled glass panels employed in my method,

Figure 2 is a front elevation of a decorated panel,

Figure 3 is a sectional detail of the three glass panels assembled with the decorated panel interposed between the protective panels, and

Figure 4 is a modified form of the invention.

35 It is well known that in art glass work, it is necessary to employ a plurality of varied colored pieces that when assembled consist of a composite design or picture. The leading of the pieces for the assembly is not only costly but oftentimes when heavy lead lines are employed the artistic appearance of the work is jeopardized.

40 In the present invention I propose to eliminate all danger of peeling, cracking or discoloring of the work, which is often caused by the subjection of the painted surface to the combined action of the sun and air.

50 I produce by my unique method of art glass assembly a construction that will fur-

nish a greater range of coloring and will be exceedingly artistic and practical.

In the accompanying drawings wherein for the purpose of illustration is shown a preferred embodiment of my invention, the 55 numeral 5 designates a portion of glass that is decorated or painted by the use of transparent colors to present an attractive picture or design.

After the design has been painted on the 60 panel 5, both the front and rear surfaces of the panel 5 are subjected to a coating of lacquer 5' and thereafter a front glass panel indicated by the numeral 6 is made to adhere to the front surface of the panel 5. 65

The numeral 7 designates a rear glass panel made of plain or colored glass that is painted as indicated by the numeral 8 with a white coating or in fact any colored coating, depending upon the effect desired to be 70 realized.

The rear panel 7 is then applied to the 75 rear surface of the panel 5, and it will be obvious that due to the presence of lacquer on the surface of the panel 5, the front and rear panels 6 and 7 will readily adhere thereto, thus presenting a unique arrangement of the panels so that a distinctive method of simulating art glass work will be 80 presented.

In practice either colored glass or plain 85 glass can be used for the protective covering, and this glass may likewise be of various texture, and when assembled as disclosed to advantage in Figure 3, it has been found that a durable and inexpensive product is realized.

In the modified form of the invention disclosed in Figure 4, the numeral 9 designates a glass panel which has painted on its rear 90 surface as indicated by the numeral 11 a decorative design. A coating of veneer 12 is applied to the rear surface and thereafter a protective panel as indicated by the numeral 13, previously coated with white paint 95 14, is made to adhere to the rear surface 10 of the plate 9.

In this form of the invention it has been found that an extra protective panel can be eliminated if desired.

From the foregoing description considered in connection with the accompanying drawing, it will be evidence that I have devised a novel arrangement of glass panels whereby a distinctive product is realized that simulates in every respect art glass work, and have produced at the same time a novel method of combining the panels so that the costly procedure of lead lines as now employed in ordinary art glass work, is eliminated.

It is to be understood that the forms of my invention herewith shown and described are to be taken as preferred examples of the same, and that various changes relative to the shape, size, material and arrangement of

parts may be resorted to without departing from the spirit of the invention, or the scope of the subjoined claim.

Having thus described my invention, I claim:

The method of producing art glass work which consists in painting a glass panel with transparent colors, applying to the front and rear surface of said panel an adhering preparation and protecting the front and rear surface of said panel by applying thereto front and rear glass panels adapted to adhere to the painted panel.

In testimony whereof I affix my signature.

JOHN MACQUARRIE.
